(57) **CLAIM**

The ornamental design for rotor of a ventilator including a portion of a blade, substantially as shown and described.

DESCRIPTION

FIG. 1 is a front view of a rotor of a ventilator including a portion of a blade according to the present design;
FIG. 2 is a left side view thereof;
FIG. 3 is a top view thereof;
FIG. 4 is a rear view thereof;
FIG. 5 is a perspective view thereof; and,
FIG. 6 is a perspective view thereof.
The broken lines which define the bounds of the claimed design form no part thereof.
